(57) **CLAIM**

The ornamental design for a sleeve for a cooler with handles and spout, as shown and described.

DESCRIPTION

FIG. 1 is an isometric view of a sleeve showing our design, the broken lines depicting a cylindrical cooler with handles and a spout showing our sleeve mounted thereon and illustrating a logo of a sports team on the sleeve forms no part of our design;

FIG. 2 is a front top isometric view;

FIG. 3 illustrates a top view thereof; and,

FIG. 4 is a right side elevation of view thereof; the left side elevational view being a mirror image.
